UNITED STATES PATENT OFFICE.

OLE VIKÖREN, OF HOLDREGE, NEBRASKA.

HORSE-BLINDER.

SPECIFICATION forming part of Letters Patent No. 721,760, dated March 3, 1903.

Application filed February 5, 1901. Serial No. 46,075. (No model.)

To all whom it may concern:

Be it known that I, OLE VIKÖREN, a citizen of the United States, residing at Holdrege, in the county of Phelps and State of Nebraska, **5** have invented a new and useful Horse-Blinder, of which the following is a specification.

This invention relates to horse-blinders.

The object of the invention is to provide a device of the character specified which shall **10** be thoroughly efficient in blindfolding a horse, thus to prevent runaways; to enable the rider or driver to control a fractious or vicious horse, and, further, to present a device which may be **15** readily operated and which shall be certain in operation for the purposes designed.

With the above and other objects in view, as will appear as the nature of the invention is better understood, the same consists in the **20** novel construction and combination of parts **20** of a horse-blinder, as will be hereinafter fully described and claimed.

In the accompanying drawings, forming a part of this specification, and in which like characters of reference indicate corresponding parts, there is illustrated one form of embodiment of the invention capable of carrying the same into practical operation, it being understood that the elements therein exhibited may be varied or changed as to shape, **30** proportion, and exact manner of assemblage without departing from the spirit thereof.

In the drawings, Figure 1 is a view in side elevation of a portion of a bridle, showing the improved blinder attached thereto and in operative position. Fig. 2 is a perspective view, on an enlarged scale, showing the blinder as it appears when folded up or in inoperative position. Fig. 3 is an enlarged transverse sectional view taken on the line 3 3 of Fig. 2. **35** Fig. 4 is an enlarged detail view, in side elevation, showing more particularly the spring-clip or holding device for retaining the curtain of the blinder within its casing.

Referring to the drawings, 1 designates a portion of a bridle including a brow-band 2 and bit-rings, only one of the latter being shown.

The blinder comprises a casing or housing 3, curved to conform to the contour of the brow-band 2 and secured thereto by spring-clips 4. The casing or housing may be made of any suitable material, preferably of leather. The ends

of the housing have secured to them straps 5, carrying buckles 6, the said straps being adapted to be secured to the bridle, and thus **55** insure a stable connection therewith. Secured within the housing is the rear end of a bellows folding curtain or blind 7, which is transversely curved to conform to the housing and in which it is normally housed, as **60** shown in Fig. 2, the shape of the curtain when in the position shown in Fig. 1 operating positively to blindfold the animal. The curtain is drawn from the housing through the medium of pull-straps 8, secured to the lower **65** ends of the curtain and thence passed through the bit-rings of the bridle and back to the riding-saddle or to the hip-straps of the driving-harness and within easy reach of the rider or driver. To prevent the curtain from working out of the housing when the animal is **70** traveling, retainers 9 are employed, which are disposed adjacent to the lower ends of the curtain and have central spring or resilient lock-loops 10, which engage transversely- **75** broadened bearing-bars 11, rigidly secured to the ends of the housing. When these retainers are in the position shown in Fig. 2, the curtain will be positively held within the housing; but when draft is applied to the **80** pull-strap the curtain will trip them to the position shown in Fig. 1, and thus permit the latter to have free outward movement.

The device of this invention is exceedingly simple in construction, is compact in form, **85** is certain of operation, and may be readily applied to any form of bridle without necessitating any change in its structural arrangement.

Having thus described the invention, what **90** I claim is—

A horse-blinder comprising a casing, means associated therewith for attaching it to the head-piece of a harness, a foldable curtain having one end secured within the housing, **95** pull-straps attached to the outer terminals of the curtain, and resilient retaining devices carried by the lower ends of the housing and adapted to be tripped when draft is applied to the pull-straps.

OLE VIKÖREN.
